UNITED STATES PATENT OFFICE.

CARL GISSKE, OF SAN FRANCISCO, CALIFORNIA.

REMOVABLE DENTAL BRIDGE.

Application filed September 22, 1924. Serial No. 739,139.

My invention relates to improvements in dental bridge work whereby one or more false teeth may be removably mounted between two spaced teeth to occupy the space and take the place of teeth extracted from a person's mouth.

The primary object of my invention is to provide an improved dental bridge.

Another object of my invention is to provide a bridge which may be readily inserted and removed from the mouth to facilitate the cleansing of the teeth and bridge.

A further object is to provide an improved bridge which may be applied without injury to the teeth between which it is secured.

A still further object is to provide an improved device of the character described which can be readily fitted and applied to the mouth and which is retained in position without permanent connections secured to the teeth and without imparting undue pressure against the sides of the teeth.

I accomplish these and other objects by means of the device disclosed in the drawings forming a part of the present specification wherein like characters of reference are used to designate similar parts throughout said specification and drawings and in which,

Fig. 1 is an enlarged side elevation showing the manner in which the bridge and teeth are mounted between spaced teeth.

Fig. 2 is a similar view, the bridge being shown in section.

Fig. 3 is a transverse section taken upon the line 3—3 of Fig. 1.

Fig. 4 is a side elevation showing the manner in which the lower plate is applied to span the space between the teeth.

Fig. 5 is a side elevation showing the manner in which the upper plate is applied in connection with the lower plate sections, the teeth to be carried by such upper plate being omitted.

Fig. 6 is an enlarged detail showing the manner in which an end of the upper plate engages and is retained by the adjacent end of the lower plate section.

Fig. 7 is a broken plan view of the interlocking means.

Referring to the drawings the numeral 1 is used to designate in general a portion of a person's jaw having natural teeth 2 and 3 separated by a space resulting from the extraction of one or more intervening teeth.

In order to fill the intervening space and

to replace the extracted teeth I provide a bridge consisting of a lower plate formed in two sections 4 and 6 shaped to conform to the gum between the teeth 2 and 3 and having their opposite ends shaped to conform to the lower portions of the adjacent teeth. One of the sections, as 4, is provided with an extension 7 having a retaining bar 8 formed thereon, said extension and bar 8 being adapted to engage and interlock with a corresponding groove 9 and recess 10 formed in the adjacent end of the opposite section 6. Notches 11 are formed upon the inner sides of the ends of the sections adjacent the teeth 2 and 3.

An upper plate designated in general by the numeral 12 is shaped to fit over the under plate, the ends 13 of the plate being made of slightly increased thickness and 75 adapted to engage the notches 11 formed in the ends of the lower plate sections.

The upper and lower plates are both cast from gold or other suitable metal by means of molds formed from wax impressions taken 80 from the mouth of a patient in the well known manner whereby the plates may be made to conform exactly to the gum and teeth and to each other.

The upper plate 12 is arranged to receive 85 one or more false teeth 14 of a size and shape adapted to replace the extracted teeth, said teeth being set and vulcanized in the well known manner, the vulcanized rubber entirely covering the upper surface of the plate 90 and being shaped and colored as closely possible to the natural size and color of the gum.

In applying my improved dental bridge, the lower plate is placed in position between the teeth by first inserting the section 6 in 95 normal position against the adjacent tooth 3 so that the shaped end of the section will fit into the curvature at the base of the tooth. The other section 4 is then inserted into position, the extension 7 first being inserted into the recess 10 and the section then pressed down from the position shown in full lines to the normal position shown in dotted lines in Fig. 4 of the drawings. A sufficient sliding movement is afforded the bar 8 within 100 the recess 10 to permit the section to be moved downwardly past the side of the tooth and then moved longitudinally to fit under and around the curvature of the tooth 2. The bar 8 is arranged to be moved against 105 shouldered lugs 16 to accurately align the sections and to limit the longitudinal move-

ment for a purpose hereinafter more fully described. The downward movement of the section is limited by an extension 17 which co-operates with the shouldered lugs 16 to hold the sections in fixed relation.

After the lower plate has been inserted as above described, the upper plate carrying the teeth 14 is inserted. This plate is inserted as shown in Fig. 5 of the drawings, one end 10 of the plate being first placed in engagement with the retaining notch 11 of the adjacent lower plate section as shown in full lines and the plate then moved downwardly to the position shown in dotted lines. The length 15 of the upper plate is made such that when moved to the dotted position it will be necessary to apply a moderate pressure to spring the end of the upper plate past the adjacent portion of the lower plate and into engagement with the notch 11.

In springing the upper plate into position the bar 8 is moved to its extreme position within the recess 10 against the shouldered lugs 16 so that the lower plates will be spaced 25 apart and firmly held in interlocked relation. At the same time the shaped ends of the lower plate section are held against the adjacent surfaces of the teeth 2 and 3. In this manner, both the upper and lower plate 30 are held firmly in position between the teeth 2 and 3, the natural curvature of the teeth being adapted to prevent either transverse or vertical movement of the bridge.

The pressure applied against the sides of 35 the teeth is regulated by the movement of the bar 8 within the recess 10. If the movement of the bar is not limited, the full spring pressure imparted by the upper plate will be directed against the sides of the teeth. In 40 some cases this arrangement is desirable and the retaining bar 8 may be entirely omitted. However, in most cases it is desirable to limit the pressure against the tooth itself and to accomplish this the bar is arranged to engage 45 the lugs 16 in such a manner as to carry the greater portion of the pressure, only sufficient pressure being applied to the tooth to hold the bridge firmly in position. If desired, the entire pressure may be directed 50 onto the bar and no pressure at all applied to the tooth, the accurate shaping of the bridge section being sufficient to hold the bridge in position without pressure against the tooth.

When it is desired to remove the bridge 55 for cleaning or for other purpose, one end of the upper plate is pried upwardly out of engagement and the plates are removed by a reversal of the above described method of insertion. The several parts may thus be 60 readily removed and replaced with very little effort or inconvenience.

My improved bridge is of particular value because of the fact that the bridge is applied without any injury to the teeth 2 and 3. In 65 common practice heretofore it has been cus-

tomary to grind portions of the teeth away to receive mounting elements of various kinds. In all such cases the sound tooth to which the bridge is anchored is itself weakened and the life of the tooth is materially 70 shortened. By my improved arrangement this injury to the tooth is entirely avoided.

While I have illustrated and described one particular form and construction, the device is of course subject to modification in 75 numerous ways, particularly with respect to the structure of the interlocking means for limiting the relative movement of the lower plate sections. I therefore do not wish to restrict myself to the specific details of structure shown in the drawings but desire to avail myself of all modifications which may fall within the scope of the appended claims.

Having thus described my invention what I claim as new and desire to secure by Let- 80 ters Patent is,

1. A dental bridge comprising a lower plate formed in two sections adapted to be detachably mounted between two teeth to span a space intervening therebetween due 90 to the extraction of one or more teeth; means formed upon adjacent ends of the sections for limiting relative longitudinal movement between said sections; and an upper plate adapted to be detachably engaged and retained by the lower plate, said upper plate being provided with teeth secured thereon to replace the extracted teeth.

2. A dental bridge comprising a lower plate formed in two sections adapted to be detachably mounted between two teeth to span a space intervening therebetween due to the extraction of one or more teeth, opposite ends of said sections being shaped to conform to the shape of the adjacent teeth 100 whereby the curvature of said teeth will retain the sections in position; and an upper plate adapted to be detachably engaged and retained between the ends of the lower plate, said upper plate being provided with teeth secured thereon to replace the extracted teeth.

3. A dental bridge comprising a lower plate formed in two sections adapted to be detachably mounted between two teeth to span a space intervening therebetween due to the extraction of one or more teeth, opposite ends of said sections being shaped to conform to the shape of the adjacent teeth whereby the curvature of said teeth will retain the sections in position; means formed upon adjacent ends of the sections to limit relative longitudinal movement between said sections; and an upper plate adapted to be detachably engaged and retained between the ends of the lower plate, said upper plate being provided with teeth secured thereon to replace the extracted teeth.

4. A dental bridge comprising a lower plate formed in two sections adapted to be 120

- detachably mounted between two teeth to span a space intervening therebetween due to the extraction of one or more teeth, opposite ends of said sections being shaped to conform to the shape of the adjacent teeth whereby the curvature of the teeth will retain the sections in position; means formed upon adjacent ends of the sections to secure said sections in interlocking relation to limit relative longitudinal movement therebetween; notches formed upon the inner sides of the shaped ends of the sections; and an upper plate adapted to be sprung into engagement with said notches to detachably secure said upper plate between the ends of the lower plate sections, said upper plate being provided with teeth secured thereon to replace the extracted teeth.
5. A dental bridge comprising a lower plate formed in two sections adapted to be detachably mounted between two teeth to span a space intervening therebetween due to the extraction of one or more teeth, opposite ends of said sections being shaped to conform to the shape of adjacent teeth whereby the curvature of the teeth will retain the sections in position; a locking element formed upon one of the sections and adapted to interlock with a corresponding recess formed in the opposite section to nor-
- mallly lock the sections against relative movement; notches formed upon the inner sides of the shaped ends of the sections; and an upper plate adapted to be sprung into engagement with said notches to detachably secure said upper plate between the ends of the lower plate sections, said upper plate being provided with teeth secured thereon to replace the extracted teeth.
6. A dental bridge comprising a lower plate formed in two interlocking sections adapted to be detachably mounted between two teeth to span a space intervening therebetween due to the extraction of one or more teeth, said sections being shaped to conform to the gum between the teeth and having opposite ends shaped to conform to the shape of the adjacent teeth whereby the curvature of the teeth will retain the sections in position and an upper plate adapted to be sprung into engagement with the shaped ends of the lower plate sections, said upper plate being shaped to conform to the shape of the lower plate and provided with teeth vulcanized thereon to replace the extracted teeth.

In witness whereof I hereunto set my signature.

CARL GISSKE.
